UNITED STATES PATENT OFFICE.

HEINRICH WEHNER, OF FRANKFORT-ON-THE-MAIN, GERMANY.

FLUSHING-VALVE.

SPECIFICATION forming part of Letters Patent No. 727,240, dated May 5, 1903.

Application filed January 20, 1903. Serial No. 139,841. (No model.)

To all whom it may concern:

Be it known that I, HEINRICH WEHNER, a subject of the German Emperor, residing and having my post-office address at 223 Röderbergweg, Frankfort-on-the-Main, Germany, have invented certain new and useful Improvements in Flushing-Valves, of which the following is a specification.

My invention relates to improvements in flushing-valves without reservoirs and floats, particularly of that kind described in my German Patent No. 136,909; and the objects of my improvement are, first, to provide the plug of the cock with a separate dragging-shell having a hole, and, second, to provide means for so actuating said dragging-shell as to move it only after the plug has nearly completed its angle of deviation for opening and closing the cock, respectively. I attain these objects by the arrangement illustrated in the accompanying drawings, in which—

Figure 1 is a vertical sectional view of a flushing-valve according to my German patent on the line C D in Fig. 2. Fig. 2 is another vertical sectional view of the same on the line A B in Fig. 1. Fig. 2^a is a detail which will be referred to later on, and Fig. 3 is a horizontal section through the flushing-valve on the line E F in Fig. 2. Fig. 4 is a vertical longitudinal sectional view of my improved flushing-valve. Fig. 5 is a vertical cross-section through the same on the line G H in Fig. 4, a part being broken away. Figs. 6 and 7 are cross-sections through a part of the same on the line K L in Fig. 4 seen from left to right, and Fig. 8 is a horizontal section through the combined piston-valve on the line I J in Fig. 4.

Similar characters of reference refer to similar parts throughout the several views.

In order to better explain my invention, I find it necessary to first describe the flushing-valve according to my German Patent No. 136,909 and with reference to Figs. 1 to

3. The inlet 1 is normally held closed by a valve 2, arranged within the casing 3 and rigidly connected by four studs 4 with an annular piston 5, which reciprocates within a regulating-chamber 6, formed by the external cylinder 7 and the internal cylinder 8. The piston is provided with a leather packing 9 for tightening the regulating-chamber

6. The internal cylinder 8 is cast in one piece with the bottom 10, the external cylinder 7, and the casing 11 of a plug-cock, the outlet of which is denoted by 12. The valve 2 is provided with a narrow opening 13, through which the supply-water is allowed to enter into the wider bifurcated channels 14 within the valve-body and two of the studs 60 4 4, and, further, into the regulating-chamber 6. The bottom 11 of the latter is provided with an aperture 15, and the plug 16 of the cock is provided, besides its bore 17, with a lateral opening 18 at right angles thereto 65 and with an elbow-channel 19, the external end of which registers with the aperture 15 in the bottom when the cock is closed. (See Fig. 2.) Such flushing-valves are specially intended to replace the well-known water-reservoirs and floats used with water-closets and to preserve their advantages, while avoiding their disadvantages. The latter are the loud noise during flushing, the liability to leakage, and the possibility of mischief by 75 allowing the water to continually run off. When a charge of liquid is required to flow off, the cock is first closed by turning the plug through an angle of ninety degrees, so that its bore 17 is at right angles to the internal cylinder 8 and the outlet 12. (See Fig. 2.) Then liquid will flow out of the regulating-chamber 6 through the apertures 15 and 19, the lateral opening 18, and the outlet 12. 80 As the aperture 15 has a larger area than the narrow opening 13, it follows that the liquid will run off quicker from the chamber 6 than liquid will enter the same. This means that the piston 5 will go downward and the valve 2 will open the inlet 1. When the plug 90 16 is again turned back to open the cock, the liquid can flow off direct from the inlet 1 through the openings between the four studs 4 4 and through the cylinder 8, the plug-bore 17, and the outlet 12. It is evident that the liquid will continue flowing until the slowly-rising piston 5 causes the valve 2 to close the inlet 1. The time during which liquid will flow off will of course depend upon the pressure in the liquid-supply. When the leather 95 packing 9 has become worn out and liquid will get from the regulating-chamber 6 to the cylinder 8, and thence through the plug-bore, the flushing-valve would cease working prop- 100

erly, and besides this there would be a continuous waste of liquid. To prevent this waste according to my said German patent, a partition (the wall 20) is arranged between 5 the two casings 3 and 7, and the valve 2 is provided with a shoulder 21, which is arranged to rest on the partition-wall 20 when the piston 5 occupies its lowermost position. Then no or very little liquid will be wasted. I have 10 found, however, that this flushing-valve still prevents the possibility of mischief by so placing the plug of the cock that it neither closes nor opens the cock completely, as is shown at Fig. 2^a. In this case the aperture 15 15 in the bottom of the chamber 6 will be closed, while there is still an outlet for the liquid through the bore 17 and the lateral opening 18. The consequence of this is that the piston 5 will stop in its respective position 20 and cannot rise and cause the valve 2 to finally close the inlet 1, because the pressure on the piston 5 from below, owing to the liquid flowing into the regulating-chamber 6 through the narrow opening 13, will be equal- 25 ized by the pressure of the liquid on the piston from above. The liquid will therefore continue flowing off through the cock and become wasted. To remedy this defect, I now provide the flushing-valve with the improvements named above, and the so-improved 30 flushing-valve is shown at Figs. 4 to 8.

The coupling 22, to be united in a known manner with the supply-pipe, is connected with the inlet-valve casing 23 by means of a nut 24. The inlet-valve 25 is in a similar manner as before provided with a shoulder 26, screwed on for resting on the partition-wall 27. Two of the four studs 28 are equally provided with channels 29, which terminate 35 in holes of the leather packing 30, secured on the piston 31 by means of an annular disk 32 and several screws 33. The area of the narrow opening 34 can in a known manner be adjusted by a screw 35. The cock-casing 40 45 36 is cast in one piece with the external cylinder 37, the internal cylinder 38, and the bottom 39 of the regulating-chamber 40^a. To the cock-casing 36 the discharge-pipe can be connected by means of the coupling 40 and 50 the nut 41. The plug 42 is to be limited in its revolution through an angle of ninety degrees in any known manner—for instance, by a projection 43 on the cock-casing, which engages in a recess of the widened-out part 44 55 of the key 45. On the side opposed to the key 45 the plug 42 has a cylindrical part 46 of a smaller diameter, on which a dragging-shell 47 is mounted to turn. This shell 47 is a ring with a sectoral part 52 cut out. Into 60 this recess a projection 48 of a disk 49 is arranged to engage. The disk 49 is secured on the plug 42 by means of a nut 50 and is prevented from turning by a face 51 on the plug extension bearing against a corresponding 65 face within the hole of the disk 49. Thus the plug 42 is rigidly connected with the disk 49. The recess 52 is much larger than the pro-

jection 48, so that on turning the plug 42 in either direction the dragging-shell 47 will first remain idle until the projection 48 strikes 70 against the respective end of the shell and takes the latter along with it. (See Figs. 6 and 7.) Thus the angle of deviation of the dragging-shell is smaller than that of the plug and is assumed to be about forty degrees. 75 Of course this angle may be varied according to the circumstances. The dragging-shell 47 is provided with a hole 53, which can register with the aperture 54 in the bottom 39. The bore 55 of the plug not only communicates with the lateral opening 56, but also with the central cavity 57, and thereby with a lateral hole 58. (See Figs. 6 and 7.)

Fig. 4 shows all the parts in their normal positions. The regulating-chamber 40^a is 85 shut off by the dragging-shell 47. (See Fig. 6.) When it is desired to discharge a certain quantity of liquid, the plug 42 is first turned with the key 45 through an angle of ninety degrees in the direction of the arrow 59 in 90 Fig. 7. From an examination of Figs. 6 and 7 it will be evident that the hole 53 of the dragging-shell will only begin to communicate with the aperture 54 in the bottom 39 after the plug has completed most of its angle 95 of deviation—i.e., about $90 - 16 = 74$ degrees—when the plug will have closed the cock and allow no water, if there were any, to flow through. Of course the operator will be obliged to completely close the cock before 100 the area of the aperture 54, opened by the dragging-shell 47, will be large enough to allow a larger quantity of the liquid to escape from the regulating-chamber 40^a than the quantity of the liquid entering this chamber 105 through the narrow opening 34. Then the piston 31 will go down and cause the valve 25 to open the inlet 22. However, as the plug 42 is still closed no water is allowed to flow direct from the inlet 22 through the cock. 110 When the plug 42 is now turned back in the direction of the arrow 60 in Fig. 6, it is evident from the above explanation that the aperture 54 will be only closed after the plug 42 has completed most of its angle of deviation. 115 This means that any mischief is rendered impossible, as no liquid will continuously flow off. By this improvement the operator will be induced to entirely open the cock. The liquid will then flow direct from the inlet 22 120 through the openings between the four studs 28 28 and through the cylinder 38, the bore 55, and the outlet 40 into the discharge-pipe. During this time the regulating-chamber 40^a is gradually filled by liquid flowing through 125 the narrow opening 34. The liquid continues flowing through the cock until at last the valve 25 closes the inlet 22. In case after closing the cock the shoulder 26 of the valve 25 should have come to rest on the partition-wall 27 it will only take a little time after again opening the cock before the liquid will commence to flow off. As already stated 130 above, the partition-wall 27 will prevent the

waste of liquid in case the leather lid 30 should have worn out and liquid is allowed to pass from the regulating-chamber 40^a to the cylinder 38. Then it will be impossible 5 for the piston 31 to rise. The operator will therefore be obliged to replace the leather packing by another one.

The flushing-valve described so far can be varied without deviating from the spirit of 10 my invention. The projection 48 of the disk 49 may be replaced by a pin or stud secured on the plug 42.

What I claim as my invention, and desire to secure by Letters Patent, is—

15 The combination with an inlet-pipe, of an inlet-valve chamber adjoining to said inlet-pipe, an inlet-valve arranged within said inlet-valve chamber for closing said inlet-pipe, an annular regulating-chamber formed by 20 an external cylinder, an internal chamber and a bottom, an annular piston reciprocating in said annular regulating-chamber and rigidly connected with said inlet-valve by means of several longitudinal studs, an annular partition-wall between said inlet-valve 25 chamber and said regulating-chamber, said inlet-valve being provided with a shoulder for resting on said partition-wall when said piston occupies its one extreme position, narrow holes provided in said inlet-valve and 30 within said longitudinal studs for admitting

liquid from said inlet to said regulating-chamber, a cock-casing adjoining to said regulating-chamber, a plug mounted to turn in said cock-casing and provided with a main 35 bore registering with said internal cylinder, also with a lateral hole at right angles to said main bore and opening to the outlet and with a central cavity communicating with said main bore, said plug having a cylindrical extension with a lateral aperture communicating with said central cavity, means for limiting said plug in its revolution through an angle of ninety degrees, a dragging-shell in the shape of a ring having a sectoral part cut 40 out and mounted to turn on said cylindrical extension of said plug and provided with a lateral aperture, and means secured on said plug for engaging in the recess of said dragging-shell while allowing the latter a certain 45 play, the said bottom of said regulating-chamber being provided with a hole registering with said lateral aperture of said dragging-shell, substantially as set forth.

In testimony whereof I have signed my 50 name to this specification in the presence of two subscribing witnesses.

HEINRICH WEHNER.
